UNITED STATES PATENT OFFICE.

FRANK R. MEASE, OF FREEPORT, ILLINOIS.

WINDOW-SHADE SUPPORT.

SPECIFICATION forming part of Letters Patent No. 705,595, dated July 29, 1902.

Application filed September 30, 1901. Serial No. 77,108. (No model.)

To all whom it may concern:

Be it known that I, FRANK R. MEASE, a citizen of the United States, residing at Freeport, in the county of Stephenson and State of Illinois, have invented certain new and useful Improvements in Window-Shade Supports, of which the following is a specification.

The object of this invention is to construct a window-shade support which will permit of the shade being raised and lowered bodily in vertical guideways and of such construction that it may be secured to the window casing or frame.

In the accompanying drawings, Figure 1 is a vertical section of my improved window-shade support. Fig. 2 is a transverse section. Fig. 3 is an isometrical representation of a section of the movable frame for supporting the shade. Fig. 4 is an isometrical representation of the removable cap supporting a roller over which the weight-cord passes. Fig. 5 is an isometrical representation of the extension to the movable frame.

A tubular shell 1 has a guideway 2 extending nearly its entire length. This tubular shell has openings, within which are located brackets 3, one near each end of the shell. These brackets are secured to the window-casing 4 or frame 5, thereby supporting the shell in a manner to permit it to have a limited oscillatory movement. Within the open upper end of the shell is located a cap 6, supporting a grooved roller 7, and a cord 8, passing over this roller, has a weight 9 secured thereto.

A frame is composed of the two sections 10 and 11, and each section has guides 12 extending along one side and fitted to slide in the guideways 2. The two sections of the frame are joined by the rod 13, which permits the sections to be adjustable to fit windows varying in width. Within the lower portion of each section of the frames is located an extension 14, having a notch 15 in its upper end and a projection 16 at its lower end. A projection 17 extends from the lower end of each of the sections of the frame. A dog 18 has a piv-

otal connection with the section, and a spring 19 holds the dog in the notch 15 of the extension when the parts are in the position shown at Fig. 1. The lower end of this extension has a guide 20, fitted to slide in the guideway 2.

When the parts are in the position shown at Fig. 1, the weight 9 connected to the cord 8 and the cord connected to the frame, the frame will be held at the upper end of the window, and the curtain supported by the frame can be raised to expose or lowered to shade the full window. By means of the projection 16 the frame can be pulled down until the extension rests on the window-frame, and by releasing the dog from its connection with the extension the frame can be drawn farther down, so as to expose more of the upper portion of the window.

I claim as my invention—

1. A window-shade support comprising two vertical guideways, tubular supports for the guideways, a frame formed with guides, a weight located within each tubular support, a roller for each tubular support, a connection between the weights and frame passing over the rollers and extensions for the frame having a movable connection therewith.

2. A window-shade support comprising two vertical guideways, tubular supports for the guideways permitting an oscillatory movement of the guideways, a frame formed with guides, a weight located within each tubular support, a roller for each support, and a connection between the weights and frame passing over the rollers.

3. A window-shade support comprising two vertical guideways, tubular supports for the guideways, a frame formed with guides, a weight located within each tubular support, a removable cap for each tubular support each supporting a roller, and a connection between the weights and frame.

FRANK R. MEASE.
